UNITED STATES PATENT OFFICE.

HENRY F. MARTEN, HENRY GRAHN, AND JULIUS C. ANDRESEN, OF SAN FRANCISCO,
CALIFORNIA.

STAVE STEAMING AND DRYING APPARATUS.

1,250,480.

Specification of Letters Patent. Patented Dec. 18, 1917.

Application filed August 8, 1917. Serial No. 185,193.

To all whom it may concern:

Be it known that we, HENRY F. MARTEN, HENRY GRAHN, and JULIUS C. ANDRESEN, citizens of the United States, residing at the city and county of San Francisco and State of California, have invented certain new and useful Improvements in Stave Steaming and Drying Apparatus, of which the following is a specification.

10 The hereinafter described invention relates to an improved apparatus for the steaming, forming and drying of staves utilized in the formation of barrels, casks, etc., and the object thereof is to provide an apparatus for efficiently and economically forming the staves to the required curvature, and for holding the same so set for the use thereof in the subsequent operation of forming barrels, and this without liability 20 of the staves breaking or cracking during the operation of applying the retaining hoop during the assembling thereof for the formation of the barrel.

Heretofore, it has been customary to steam 25 the staves and also dip them in water to obtain the requisite pliability of the wood, the staves during the steaming operation being held within a suitable form and in an initiated assembled position; after the steaming 30 operation, the staves are drawn together in order to place hoops thereon and it is the sudden strain to which they are subjected during this drawing together and bending 35 of the steamed staves which tends to break or crack the same.

Under the present invention, the idea involved is to place the staves loosely held to a suitable curved former, and as thus held, convey the same into a steaming apparatus, 40 the duration of travel through the said steaming apparatus, being so timed and of a sufficient length of time as to cause perfect steaming of the wooden staves for obtaining the requisite pliability thereof for bending 45 purposes. As the staves are successively passed through the steaming apparatus they are subjected at each end thereof progressively during the course of travel to the ac-

tion of means which will gradually but positively depress the outer end portions thereof 50 to the surface of the form, thus gradually bending or causing the same to assume the shape of the form to which they are held, and as depressed relative to the form, means are automatically thrown into action to positively hold the formed staves in their altered 55 or bent position, so that by the time the staves reach the outlet or discharge opening of the steaming apparatus they are bent to approximately conform to the curvature of 60 the form on which they rest, which is the proper curvature into which the staves are to be placed for the formation of barrels therefrom. As the forms with the pressed 65 staves held thereto leave the steaming apparatus or rather the steaming section of the steaming and forming apparatus, they are moved or carried into a drying chamber or drier, and during the course of travel therethrough the wooden staves are thoroughly 70 dried, so that when carried from within the drier, the staves are set to the curvature of 75 the form and on the release from the form are in set condition for assembling purposes for the construction of barrels therefrom.

In its preferred embodiment, the apparatus is entirely automatic after the placing of the staves on the forms, so that when the staves pass through the steaming apparatus into the drying machine or drying box and 80 as carried from said box they are automatically released to permit the removal therefrom by an operator positioned for such purposes.

In order to comprehend the invention reference should be had to the accompanying sheets of drawings, wherein,

Figure 1 is a broken side elevation of the steam and drying chambers, illustrating diagrammatically the travel of the endless carriers for conveying the forms with the staves applied thereto into and through the steaming chamber, and from said steaming chamber into and out of the drying chamber, the arrows indicating the line of travel of the 90 endless carriers, and said view illustrating 95

in connection with the steaming chamber the means for progressively depressing the ends of the staves carried by the forms, as moved through said chamber.

5 Fig. 2 is an enlarged cross-sectional elevation illustrating one of the forms attached to the endless carrier with a stave loosely applied thereto, the means for depressing the ends of the staves as moved through the 10 steaming chamber, the lock devices for holding the staves in locked depressed position and the supports for the forms during course of travel through the apparatus.

Fig. 3 is a broken part sectional view of 15 one of the forms disclosing an enlarged detail of the lock means for holding the ends of the staves in depressed position as carried through the steaming chamber.

Fig. 4 is an enlarged detail sectional view 20 taken on the irregular line 4—4 Fig. 3 of the drawings and viewed in the direction of the arrow.

In the drawings the numeral 1 is used to designate the steaming chamber of the apparatus and 2 the drying chamber thereof, there being disclosed a water seal 3 interposed between the outlet of the steaming chamber and the inlet of the drying chamber. Within the steaming chamber is 30 mounted in vertical planes, the sprocket wheels 3', which are mounted on the cross-shafts 4, and over which travel the endless chains 5. These chains or carriers are provided at intervals throughout their length 35 with inwardly projecting flights or extensions 6, to which are bolted, or otherwise secured the ends 7 of the stave forms 9; the upper surface or section 9' of each form being curved or shaped for the curvature to 40 be given the held stave 10; the ends of which staves are fitted within the open keepers 11, secured to the upper end of the depressible blocks 12. The stem 12' of the blocks or 45 gage pieces 12 work through the vertical openings, bores or, slots 13 formed in the end portion of the forms 9 and are movable freely therein, being held at their lower ends from dropping or falling from within the bores, openings or slots 13 when in an inverted position by means of the wedge pieces 50 14 fitted within and projecting laterally beyond the slotted portion 15' of the stems 12'. The gage pieces or blocks 12 are held normally in a raised position by means of the 55 staves 10, which staves rest on the highest portion of the curved section 9' of the forms 9, consequently, the gage pieces or blocks 12 when the ends of the staves are fitted therein are held upwardly or in the position illustrated in Fig. 2 of the drawings.

To the under-face of the forms 9 and at each end portion thereof is mounted for free lateral swinging movement, a lock cam 15, the casting of which is formed with the pro-

jecting trunnions 16', which said trunnions 65 work within bearing boxes 16 bolted to the underface of the forms 9 and at each end portion thereof. The cam casting 15 is bifurcated so as to straddle the stem portion 12' of the gage blocks 12, and the inner edge 70 or face 17 of each portion 17' of the bifurcated cam 15 engage with the wedge blocks 75 of serrations 18, forming a series of notched portions or shoulders which engage progressively with the upper edge of the wedge pieces or wedge blocks 14, on the gage blocks 12 being depressed into a position which will allow or permit of the wedge shaped cam moving inwardly to place one of its shoulders 18 into engagement with the upper surface of the wedge blocks 14. When the notches or shouldered portions of the bifurcated cam 15 engage with the wedge blocks 14, the gage blocks 12 are held against upward movement by reason of the pressure of 85 the staves placed thereon.

In Fig. 1 of the drawings, the outer extended or feed portion of the endless carrier is broken away, but it will be understood that the staves to be steamed and dried are 90 placed by an operator on to the outer upper run portion of the traveling carrier, the ends of the staves being fitted within the open keepers 11, with the central portion thereof resting on the uppermost curved surface of 95 the section 9' of the form 9. As thus held, the staves are carried by the movement of the endless carriers over the lower sprocket wheels 3' into the steaming chamber through the inlet opening a, and are carried upwardly within the said steaming chamber and over the upper spaced sprocket wheels 3', and during the travel between the said upper spaced sprocket wheels 3' the keepers 11 are moved beneath the pressure rolls 19 100 mounted on the cross-shaft 20, a downward pressure being thus exerted on the said keepers to depress the blocks 12 such a distance as will permit of the weighted swinging cams 15 to move inwardly until the first 105 notch or shoulder of the series of notches or shoulders 18 thereof will move over the upper edge of the wedge blocks 14, the ends of the staves being depressed with the downward movement of the gage blocks 12. As 110 the keepers with the staves therein are carried beyond the sphere of the uppermost set of compressing rollers 19, the staves will have been slightly bent or curved to a given 115 distance and held in this position by the locked engagement of the cam 15 with the wedges 14, and as thus held they are carried by the movement of the endless traveling carriers until the keepers 11 are brought into 120 contact with the second set of pressure rollers 19, located in a lower plane from that of the first mentioned compressing rollers, and as carried beneath said compressing rollers 125

the keepers 11 are forced downwardly a greater distance, causing the wedges 14 of the gage blocks 12 to move downwardly such a distance as to permit the second notched or step portion 18 of the cam 15 to swing over the upper edge thereof, and which engagement of the notched portion of said cam 15 with the wedges 14 hold the keepers 11 in said depressed position as carried beneath 10 and from the second set of said compression rollers 19, and they are held so depressed during the travel of the endless carrier until brought into contact with the third or lowermost set of said compression rollers 19.

As moved beneath these compression rollers, the keepers 11 are again depressed a given distance, so as to cause the downward movement of the gage blocks 12 to position the upper edge of the wedges 14 to such a point as will permit of the third notch or shouldered portion of the series of notches or shoulders 18 of the cam 15 to swing inwardly over the upper edge of said wedges. It will thus be noted that as the endless carriers move through the steaming chamber or box 1, the staves are progressively depressed to gradually conform to the shape of the form section 9' of the form 9, so that by the time they are carried beneath the lowermost 20 set of compressing rollers 19, the staves are in contact with the section 9' of the form 9 approximately throughout the length thereof. It will be understood that the time of travel of the endless carrier through the 30 steaming box 1 is of such a duration as to permit of the steam acting on the staves 10 to place the wood in a thorough pliable condition, so that the same readily gives or bends under the pressure of the various 40 rollers 19 placed thereon and thereby gradually shaped to the curvature of the formed section 9' of the form 9, sudden strains on to the staves being thus avoided and the breaking or cracking thereof prevented during 45 barrel assembling. To provide against sagging of the endless carrier as moved through the steaming chamber by the sprocket wheels 3', there is interposed at intervals throughout the length of travel, the spaced supporting rolls 21 which are mounted on the cross shafts 22, Figs. 1 and 2 of the drawings. 50 These rolls 21 are arranged within the steam chamber 1 so as to lie beneath the endless carriers at points adjacent the present rollers 19, thus supporting the form 9 at such portion of the travel of the carriers and preventing the downward give thereof on the pressure of the rollers 19 being exerted on the keepers 11 to depress the ends of the 60 confined staves.

While the term carriers has been employed to designate the endless traveling members 5, it will be understood that these members in conjunction with the transverse

forms 9 united thereto, constitute the endless 65 traveling conveyer and hereinafter the term "endless carrier" will be employed to designate the means for moving the staves to be steamed throughout the steaming chamber, whatever the form thereof may be. The 70 endless carrier as it leaves the lowermost set of sprocket rolls 3', passes from within the steaming box through the water seal 3 through the outlet opening 24 of such box and into and through the inlet opening 25 of 75 the drying chamber 2, and travels through the said chamber over the sprockets 3' arranged therein to give a circuitous path of travel to the endless carrier. The duration of travel of the endless carrier through the 80 drying chamber 2 is sufficient for the heat of the chamber to act on the steamed and formed staves to thoroughly dry the same for the setting thereof to the curvature of the form section 9' of the forms 9. The endless 85 carrier with the dry and set staves thereon moves from within the drying chamber through the outlet opening 26 thereof and after leaving said chamber the dried and set staves are carried by the endless carrier toward the feed end of the apparatus. During the travel of the endless carrier toward the feed end of the apparatus, the keepers 11 and the cams 15 stand in a reversed position to that in which they were placed when 90 passed beneath the compressing pressure rollers 19 situated within the steaming chamber, and as carried toward the feed end of the machine the keepers move over two spaced rollers 27 mounted on the cross-shaft 100 27' suspended in bearings or brackets 28, and the said rollers 27 acting successively on the said keepers 11 force the same upwardly and move the wedges 14 from off the notched portion of the swinging cam 15, with the result that the weight of the cam swings the same downwardly free of the said wedges 14, when the weight of the forms and staves will cause the free downward movement of the gage blocks 12 and the keepers 11, removing the formed stave from contact with the curved section 9' of the formers 9. The 105 formed and set staves are thus free to be removed by the operator from within the keepers 11, as brought toward the feed end of the 110 machine.

By means of the suitable adjustable bolts the bearings 29 for the cross-shafts 20 carrying the compressing rollers 19 and which bearing boxes are located outside of the forming chamber Fig. 2 of the drawings, may be adjusted vertically to vary the position of the compressing rollers 19 relative to the travel of the endless carrier through the 115 steaming chamber, so as to permit of an increased or decreased pressure of the rollers relative to the keepers 11 traveling there- 120 beneath.

The endless carrier is driven by any suitable mechanism not shown, and the speed of travel is so proportioned as to subject each stave passing through the steaming 5 chamber and through the drying chamber to at least an exposure of fifteen minutes to the action of the steam within the steaming chamber and to the heat within the drying chamber, and the capacity of the said chambers for the staves to be steamed and dried 10 is such, that approximately 850 staves are moving within the said steaming chamber for steaming purposes at one time.

As a steamed and set stave reaches the 15 operator positioned at the feed station of the apparatus, the same is removed and a stave to be steamed and dried inserted in place thereof, consequently, there is a continuous line of staves moving into the apparatus to replace the ones removed from the endless carrier.

The apparatus is simple in construction and positive in its operation and accomplishes the work of steaming, bending and 25 the setting of the staves without danger or liability of the breaking or cracking thereof, which is an essential factor relative to the assembling of the same for the manufacture of barrels therefrom.

30 It will be understood that any well known system of admitting steam to the interior of the steaming chamber may be employed, and for such reason no illustration of steam supply pipes has been made, such being left 35 optional with the constructor of the apparatus. Equally so, any suitable form of drive connections may be employed for transmitting rotation to the shafts carrying the sprocket wheels for the carrier chains, 40 it not being necessary to illustrate the same in the drawings.

The apparatus has been described and illustrated in its preferred embodiment, but it is obvious that various changes may be 45 made in the construction of the detailed working parts and this, without creating a departure from the nature and spirit of the invention, which it is desired to claim as broadly as the state of the invention will 50 permit.

Having thus described our invention what is claimed as new and desired to be protected by Letters Patent is:

1. An apparatus for the steaming of 55 wooden staves, the same comprising a steaming chamber, an endless carrier movable into, through and out of said chamber in a circuitous path of travel, spaced stave forms carried thereby, means for holding the stave 60 to be steamed to said forms, spaced devices within the chamber with which said staves are successively forced into contact at intermediate intervals during the movement of said carrier for progressively at intermittent

intervals depressing the ends of the held 6 staves to conform to the shape of the stave forms during the travel thereof within the steaming chamber, means associated with each form for holding the staves locked in depressed position while moved from one to 70 a successive depressing device, and releasing means situated outside of said steaming chamber for successively releasing the lock means for the stave during the travel thereof from the outlet of the steaming chamber 75 toward the inlet opening thereof.

2. An apparatus for the described purpose, the same comprising a steaming chamber and an associated drying chamber, each provided with an inlet and an outlet opening, an endless carrier movable successively into, through and out of said chamber in a circuitous path of travel, spaced stave forms secured to and carried by the endless carrier, means associated with each form for 80 securing a stave thereto, pressive devices within the steaming chamber and at spaced intervals along the travel of the carrier for progressively depressing at intermittent intervals the stave to conform to the stave 85 formers during travel thereof through said chamber, devices associated with the stave securing means for holding same locked in depressed position while being conveyed between said pressive devices, and means for 90 releasing said lock devices during travel of the endless carrier from the outlet of the drying chamber toward the inlet of the steaming chamber.

3. An apparatus for the described purpose, the same comprising a steaming chamber, of means for gradually advancing stave forms through said chamber, securing means associated with each form for holding a stave thereto, pressive means positioned at 100 spaced intervals within the steaming chamber for progressively depressing at intermittent intervals the staves relative to the shape of the forms during the travel thereof through the said chamber, and devices associated with the stave securing means for holding the same locked in depressed positions while moved to successive pressive devices.

4. An apparatus for the described purpose, the same comprising a steaming chamber, of means for advancing stave forms throughout in spaced relation, stave keepers associated with the outer end portion of the stave forms for the retention of staves to 110 be steamed thereon, pressure means positioned at spaced intervals within the steaming chamber in the path of travel of the stave advancing means for progressively depressing the stave keepers at intermittent intervals during the advancing movement of the stave forms through the said chamber, and devices for holding the stave keepers 115 120 125

locked in depressed position while moved to successive pressure means.

5. An apparatus for the described purpose, the same comprising a steaming chamber, of means for advancing stave forms throughout in spaced relation, stave keepers associated with the outer end portion of the stave forms for the retention of staves to be steamed thereon, pressure means at intervals within the steaming chamber for progressively depressing the stave keepers at intermittent intervals during the advancing movement of the stave forms through the said chamber, devices for holding the 5 stave keepers locked in depressed position, a drying chamber associated with the steaming chamber, means for advancing the stave forms with the steamed staves locked thereto through the drying chamber, and devices 20 for releasing the dried staves from the stave forms.

6. An apparatus for the described purpose, the same comprising a steaming chamber, a series of stave forms, means for continuously advancing said forms through the steaming chamber in spaced relation, depressible lock devices for holding staves to said forms, and means at spaced intervals within the steaming chamber for progressively depressing the stave at intermittent intervals relative to the forms as continuously moved through said chamber.

7. An apparatus for the described purpose, the same comprising a steaming chamber, a series of stave forms, depressible devices for holding staves to be steamed to said forms, mechanism for advancing the forms with staves applied thereto in spaced relation through the steaming chamber, and 40 fixed means arranged at intervals within the said chamber throughout the length of the advancing means for progressively depressing the stave holding devices at intermittent intervals relative to the forms during the 45 continuous movement thereof through the steaming chamber whereby the staves are gradually curved to conform to the shape of the forms.

8. An apparatus for the described purpose, 50 the same comprising a steaming chamber, a drying chamber associated therewith, a series of stave forms, means for moving the said forms successively in spaced relation through the said steaming and drying chambers, depressible devices associated with each form for engaging only the opposite ends of a stave for holding the same thereto, and means within the steaming chamber for progressively depressing the stave holding devices to gradually bend the same at successive intervals during its travel through the steaming chamber to conform to the shape of the stave forms during the travel thereof through the said steaming chamber.

9. In an apparatus for the described purpose, the combination with a steaming chamber, of a series of stave forms held in spaced relation, mechanism for advancing the same through the steaming chamber, depressible means associated with each stave form for holding a stave to be steamed thereto, devices operated at intervals for progressively depressing the successive stave holding means during the movement through the steaming chamber for gradually bending the 70 staves to conform to the curvature of the stave forms during the movement thereof through the steaming chamber, and lock means associated with the stave holding means for the holding of the same in depressed position.

10. An apparatus for the described purpose, the same comprising a steaming chamber, mechanism for moving forms with staves applied thereto through said steaming chamber in spaced relation, spaced pressure devices within said chamber for acting successively to progressively bend the staves to gradually conform at intermittent intervals to the shape of the stave forms during the travel thereof through said chamber, and means associated with said forms for holding the staves in position relative thereto.

11. The combination with a steaming chamber of an endless carrier having united thereto a series of spaced stave forms, depressible means at the opposite ends of said forms for holding staves thereto, pressure devices at intervals within the steaming chamber and into contact with which said 100 depressible means successively engage during the travel of the endless carrier through the steaming chamber to gradually bend staves to conform to the curvature of the stave forms, and a swinging lock cam associated with each of the depressible means for engaging therewith to hold the same in any of the depressed positions.

12. The combination with a steaming chamber of an endless carrier having united thereto a series of spaced stave forms, depressible means passing through the opposite ends of said forms for holding staves thereto, and devices carried on the rear of each form and engageable with the depressible means extended therethrough for the holding of the same in depressed position during the movement of the stave forms through the steaming chamber.

13. An apparatus for the described purpose, the same comprising a steaming chamber, a drying chamber associated therewith, mechanism for successively advancing in spaced relation stave forms with staves applied thereto through the steaming chamber, compressing means positioned at intervals throughout the path of travel of the advancing means and the drying chamber for bend-

ing the staves at intervals to gradually conform to the curvature of the stave forms during movement through said chamber, and devices associated with each stave form for holding the staves in any adjusted or bent position relative to the forms while passing between said compressing means.

In testimony whereof we have signed our

names to this specification in the presence of two subscribing witnesses.
